**METHOD AND APPARATUS FOR WINDING
TEXTILE BOBBINS**

Richard Carl Gütermann, Zollikon, Zurich, Switzerland

Application January 29, 1953, Serial No. 333,952

Claims priority, application Switzerland February 1, 1952 10

27 Claims. (Cl. 242—18)

The invention relates to a method of making a wound bobbin, in particular a wound cardboard, together with an arrangement for carrying out the method.

A preferred form of embodiment of the device or arrangement according to the invention is illustrated in the accompanying drawings, wherein Figs. 1-3 show an essential part of the device, namely the winding spindle with a controllable clamping part for the bobbin or cardboard tube to be wound, while Figs. 4-26 illustrate the thread securing apparatus as well as different stages of the method.

Fig. 1 is a longitudinal section of the winding spindle with the bobbin tube set thereon;

Fig. 2 is a longitudinal section of the actual clamping part shown on an enlarged scale, while

Fig. 3 shows a cross-section taken on the line A—A of Fig. 2.

Figs. 4 and 5 show, as viewed at the side and from above, the cutting member in the position for making the tongue in the cardboard tube to secure the starting end of the thread;

Figs. 6 and 7 show the cutting member, in side view and as seen from above, in the position for making the tongue to secure the final end of the thread.

Figs. 8 and 9 show the thread clip as viewed at the side and from above, while

Fig. 10 is an end view of the nippers of the thread clip.

Fig. 11 shows diagrammatically in side view the tongue presser for securing the final thread end.

Fig. 12 is a side view of the shears;

Fig. 13 is a side view of the thread clamp;

Fig. 14 is a side view of the tongue presser for securing the starting thread end;

Fig. 15 is a top view of the members according to Figs. 8-11 arranged beside each other;

Figs. 16-20 show various stages in the operation of securing the final thread, while

Figs. 21 and 22 illustrate diagrammatically the process of tightening, clamping and severing the thread after the end has been secured.

Figs. 23-26 show different stages of the method of securing the initial thread up to the starting of the winding operation.

Fig. 27 shows the means for actuating the winding spindle shown in Fig. 1;

Figs. 28 and 29 show the means for moving the thread holding device as a unit with respect to the winding spindle;

Fig. 30 shows the parts of the thread holding device including the driving means and a winding spindle;

Fig. 31 is a diagram showing the developed perimeters of ten cams one above the other.

First of all, the design and method of working of the winding spindle and of the thread securing apparatus will be described followed by a disclosure of the whole method.

Referring to said annexed drawings, according to the form of embodiment of the winding spindle as in Figs.

2

1-3, this incorporates a guide and bearing sleeve 1 (hereinafter called bush) rotatably carried in the machine gearbox 1a and designed to receive its rotational drive through a gearwheel 1c firmly connected thereto by set screw 1b.

5 Said bush 1 projects with its head 1d beyond the gearbox 1a and forms at 1e an abutment for the bobbin tube 9 to be wound, and at 1f a shoulder as abutment against the corresponding end wall of the gearbox. The bush 1 is secured against endwise displacement by a set ring or collar 1g. The bush 1 has fixed thereon a nose 2 projecting inwardly and engaging a longitudinal groove 2a of the actual spindle sleeve 3 so that the latter is rotatably connected to the bush 1 and axially displaceable with respect thereto within the limits of the abutments 2b and 2c. At its front end—at the right in the drawing—the spindle sleeve 3 carries an expansible member 7, 8 in the form of an expansible body slit to a spring-cage 7, 8 (shown more particularly in Figs. 2 and 3) which serves for taking and clamping the bobbin tube. The spindle sleeve 3 carries a mandrel 5 for endwise movement therein. At its front end, the mandrel 5 has a tapered expander head which works together with enlargements 8 of the spring-cage. The mandrel with the expander head 6 is—both together with the spindle sleeve 3 as an unit and also independent of it and its sliding movement—axially displaceable in such a way that it can, with the spring-cage 7, 8 at any desired position outside the sleeve head 1d, expand or tighten said cage or loosen it. For the corresponding independent control on the one hand of the spindle 3 with the spring-cage 7, 8 and on the other hand of the mandrel 5 with the expander head 6, the following devices are provided:

By means of a set screw 4b, a control head 4a is fixed on the portion of the spindle sleeve 3 projecting behind from the box 1a. Said control head 4a is rotatably carried in a stationary sleeve 4c which, with diametrically disposed pins 4d, is surrounded by the fork 4e of a control lever 4f, said lever receiving a swivelling drive from the axle 4g, whereby the spindle sleeve 3 during its rotary movement with the bush 1 is longitudinally displaceable with respect to the bush 1. The mandrel 5 projects behind beyond the spindle sleeve 3 and carries at its end a screw thread for engagement with a cap 5a. The cap has a lengthening which extends over the end of the bush and terminates in a shoulder 5b against which lies a control lever 11 that receives a swivelling drive through the axle 11a.

Inserted between the end of the sleeve 3 and the rear portion of cap 5a is a spring 10 which tends to draw the mandrel 5 with the expander head 6 to the back with respect to sleeve 3, i. e. into a position in which the expander head 6 stresses, i. e. expands the spring-case on account of the enlargements 8 running on to the head 6.

55 In this stressed or bobbin-tube clamping position produced by spring action, the lever 11 has the position as in Fig. 1. If the lever 11 is swung to the front, i. e. to the right according to the drawing, coming to bear on the shoulder 5b and under tensioning of the spring 10, the mandrel 5 moves to the front with respect to the sleeve 3, thus relieving the spring-cage from stress so that the bobbin tube 9 fitted on it is no longer held clamped.

60 From the described design of the winding spindle it may be seen that the clamping part 3, 7, 8, as well as 5, 6 is axially displaceable as a whole into any desired position by the control lever 11, when the latter is in its inoperative (dotted-line) position.

65 By swinging the control lever 11 into its operative position, thus bringing it to bear against the shoulder 5b of the cap 5a, the mutual displacing of the mandrel 5 with the expander head 6 in relation to the spindle sleeve 3 with the spring-cage 7, 8 takes place in the sense of

an expanding of the cage. Because of this it is possible to fit the bobbin tube 9 as deeply as desired onto the clamping part, i. e. to hold it clamped in any position, whether only half the tube for instance, or the whole of it, is fitted on.

Let the particular modus operandi of the winding mandrel be explained with reference to a disclosure of the method, say for making a cross-wound bobbin of the usual commercial type.

Prior to starting the winding, the spindle sleeve 3 with the spring-cage 7, 8 and the mandrel 5 with the expander head 6 are retracted into the bush 1 by lever 11, the spring-case being then detensioned and the lever 4f takes up the dotted-line position. In this way, the clamping part 3, 7 and 8 as well as 5 and 6 are out of action.

Now if an empty cardboard tube 9 fed from a magazine or by a gripper arrives in front of the head 1d of the bush 1, the clamping part, i. e. the spindle sleeve 3 with the spring-cage 7, 8 together with the mandrel 5 with expander head 6, is pushed into the empty tube 9. Then the control lever 11 is swung into its dotted-line position, so that the spring 10 gets detensioned. Incidentally the mandrel 5 moves backwards with respect to the spindle sleeve 3, so that the expander head 6 runs onto the enlargements 8 of the spring-cage 7 and causes the cage to open out, whereby the tube 9 gets clamped in its axial position which, in fact, does not correspond to that shown in Fig. 1, but to the position as in Fig. 4, so that tube 9 is not set on so deeply. In this position of the tube 9 on the clamping part of the winding spindle, the beginning of the thread to be wound is secured in any desired manner. This may be accomplished, for instance, in that a tool stamps out a tongue 2 somewhere in the middle of the tube 9, and through this the beginning of the thread will be held, i. e. secured (see tongue 2 in Figs. 4, 22-25).

For the more accurate and symmetrical positioning of the bobbin part 9 in relation to the winding member (not shown), the clamping part of the winding spindle may be released as aforementioned, so that the clamping part is pushed deeper into the tube, and then a member simultaneously acting on the tube 9 causes same to rest on the front end 1e of the head 1d of the bush 1 so as to determine the position of tube 9 definitely.

The winding position of the tube on the clamping part of the winding spindle is illustrated in Fig. 1.

Now the tube 9 can be wound with the thread. The tube 9 having been wound with the desired length of thread, the securing of the end of the thread to the free extremity of the tube will be effected in any desired manner, say, by a tool which stamps a tongue 2a into the tube extremity in which the thread end is secured. Then the thread is severed (Figs. 6, 15-19).

Now the clamping part of the winding spindle is again loosened and retracted by control lever 4f into the sleeve 3 so that the finished wound bobbin, i. e. the wound tube 9, becomes free and falls, for instance downwards, out of the machine to be then led to the packing station, if necessary.

The thread securing apparatus disclosed below in detail with respect to design and method of working, according to Figs. 4-15, is provided with a cutting member 12 for cutting the tongue 2 to secure the starting end of the thread (Figs. 4 and 5), and the tongue 2a for the final end of the thread (Figs. 6 and 7), further with a thread clip 14 cooperating with the thread guide 13 of the winding machine, as well as with two tongue pressers 15 and 16, of which the one adapted to press down the tongue 2 for securing the starting thread end has the reference numeral 16, while the other for pressing down the tongue 2a to secure the final thread end has the numeral 15. In addition to the aforementioned members, the thread securing apparatus also includes a thread nipper 17 with shears 18.

Preferably, the described thread securing apparatus is

mounted on the winding machine in front of each winding spindle (Fig. 1). During the winding period of the machine, the automatic thread securing apparatus remains disengaged. As soon as the set number of metres 5 has been wound, the winding spindle is brought to rest, whereupon the control members will be engaged for operating the thread securing apparatus.

The member 12 for cutting the tongues 2, 2a in the periphery of the bobbin tube 9, is represented in Figs. 4 and 5 as positioned for cutting the tongue 2 to secure the starting thread end, and in Figs. 6 and 7 as positioned for cutting the tongue 2a to secure the final thread end.

The cutting member 12 comprises two knives 19 and 20. The actual tongue-cutting knife 19 is formed as a lever swivably mounted on an axle 21 in a block 22 firmly located in the frame (not shown) of the thread securing apparatus. The block 22 includes a bracket which serves as counter-knife 20 to the knife 19 and 15 has two lateral cutting cheeks between which the knife 19 can swing. Journalled in block 22 is the control axle 23 which, with an arm 24, drives the knife 19, i. e. swings it up and down through the intermediary of a link 25. The cutting member 12 is so provided that the knife 19 can be introduced into the bobbin tube 9, the thread securing apparatus being approached to the tube 9 in such a way that the counter-knife 20 rests outside against the tube 9.

When swung up round the axle 21, the knife 19 introduced into the tube 9 cuts a tongue 2 or 2a from inside to outside out of the periphery of the tube 9 and bends, with its inclined face 19a, the tongue away upwards from the periphery of tube 9.

The block 22 is mounted as an independent block on 35 the frame or bedplate of the thread securing apparatus.

The thread clip 14, illustrated in detail in Figs. 8 and 9, includes two nippers 26 and 27 so designed that in the closed position of the two nippers (Fig. 8), an opening 28 is provided by which the thread is held in loose 40 guiding. The nipper 27 forms part of a lever 27a swivably mounted on control axle 29 in a block 30 located on the frame or bedplate of the thread securing apparatus.

The nipper 26 is swivably arranged on an axle on 45 nipper 27. The nipper 26 is swivelled by a push rod 32 which by means of pin-and-slot connections 33 can be pushed along the lever 27a and engages at the front end a slot 34 in a pin 35 of the nipper 26, while the rear end projects beyond the lever 27a and, with a pin 36, bears on arm 37 of a control axle 38 journalled in block 50 30. A tension spring 39 engages at one end at 40 the push rod 32 and at the other end 41 the lever 27a. The spring 39 continually retracts the push rod 32, whereby the pin 36 rests against the control arm 37. The spring 39 therefore tends to keep the nipper 26 in the closed position.

The position of the parts shown in Figs. 8 and 9 corresponds to the closed position of the thread clip. If the control arm 37 is moved in the direction of the arrow P by the control axle 38, the nipper 26 opens by movement of the push rod 32 (dotted line position in Fig. 8).

The set-up of the further members of the thread securing apparatus will be better understood, first of all with reference to the illustrative embodiment as in Figs. 12 and 13.

United to the block 30 or integral therewith is a block 65 part 42 firmly connected to the bedplate or frame of the thread securing apparatus. By a bracket 43, the part 42 forms the fixed support of a blade 44 of the shears 18, the blade being exchangeably fixed thereon. On the bracket 43, the second plate 46 in the form of a lever is fulcrumed to an axle 45, the end of said lever being connected through a link 47 to the arm 48 of the control axle 49. By the up and down movement of the control arm 48, the closing and opening movements of the shears are effected in a positive manner (Fig. 12).

The thread gripper 17 as in Fig. 13 includes moreover

a stationary clamping part 50 formed by the bracket 43 of block 42; on said part 50, the axle 51 has a lever 52 pivoted thereon and forming with respect to the clamping part 50 the second clamping part 53 having preferably a rubber sleeve to ensure perfect seizing and clamping of the thread. The other extremity of lever 52 projects into the path of a pin 54 of the control arm 48 of axle 49.

A spring 55 arranged between the bracket 43 or block 42 and lever 52 urges the lever 52, 53 continually against the control pin 54, so that the thread gripper 50, 53 is normally held by said spring in its closed position. By the up and down movement of the control arm 48, the thread gripper 50, 53 is opened and closed.

Both the movable blade 46 (Fig. 12) and the movable thread gripping member 52, 53 (Fig. 13), each controls one of the tongue pressers 15 and 16 as described in what follows:

The tongue presser 15 for securing the final end of the thread (Fig. 11) comprises a two-armed lever 56, 57 pivotally carried on axle 58 in the bracket 43 of the block 42. The arm 56 is provided in the front part with a stamp, the actual tongue presser 15. The free end of the arm 57 is spring (60) biassed so that its cross-pin 59 bears on blade 46 (Figs. 11 and 12). In the opened position of the shears as in Fig. 12, the tongue presser 15 is in disengaged condition. On closing the blade 46 through the control arm 48, the lever 56, 57 with the tongue presser 15 is caused to move anticlockwise into operative position.

The tongue presser 16 for pressing down the tongue 2 to secure the starting end of the thread is in a similar way pivotally connected to the thread gripping member 52, 53, as is the tongue presser 15 to the blade 46. The presser 16 includes a two-armed lever 61, 62 capable of swivelling round the axle 63 on the bracket 43 of block 42 (Fig. 14).

Attached to the thread gripping member 52, 53 is a cross-piece 64 (Figs. 13 and 15) having a set screw 65 lying with its bottom part 65a in the path of the arm 61 of the tongue presser 16.

Attached to the free extremity of the arm 62 of the presser 16 is a tension spring 66 with its other end engaging the block 42. Due to the action of spring 66, the presser 16 tends to remain in its disengaged position.

On opening the thread gripping member 52, 53, the tongue presser 16 is pressed down by set screw 65 into operative position on the tongue 2 to secure the starting end of the thread.

The different members according to Figs. 11-14, i. e. the tongue presser 15, the shears 18, the thread nipper 17 and the tongue presser 16 are disposed alongside each other on block 42 and constitute a unit as in Fig. 15.

The mode of operation of the different members together with the thread guide 13 of the winding machine will be explained hereinafter with reference to a complete winding operation, whereby it must be pointed out that the different members are—through the control axles disclosed singly hereinbefore—actuated by control members which are moved for instance by different cam eccentrics of at least one preset program roller. Independent of this, the whole thread securing apparatus is also brought, together with said members, by means of preset program control members into the different positions necessary for carrying out the winding process.

For describing the method, we start from that step in which the thread guide 13 (Figs. 16-26) of the machine, after the winding of the bobbin tube 9, remains at rest at any desired position with respect to the winding machine (not shown) (Fig. 1). The thread guide 13 is brought to the free fore end of the tube, the winding machine being run at a slow speed until this position is reached.

From this position the thread guide 13 will be raised a definite distance from the winding of the tube 9 (Fig. 16). The thread securing apparatus is then moved by

its control members so that the knife 19 of the cutting member 12 comes into the position as in Figs. 6 and 7, i. e. into the front edge of the tube 9, held by the gripping member 7 of the winding spindle 1d. Thereby the tongue 2a is cut by the blades 19 and 20 actuated through the control axle 23, and is bent up, whereupon the knife 19 is again brought down into the position shown in Figs. 6 and 7 and moved away by the thread securing apparatus. The thread clip 14 (Figs. 8-10) now opens for the placing of the thread, engages with open nipper 26 over same and is closed, whereupon the clip is swung about the axle 29 and the thread will be brought over the extremity of the tube 9 to the other side of the tube (Fig. 17). Then the thread clip 14 moves approximately parallel to the axis of the tube (Fig. 18) and away from the end of the tube, until the thread portion 67 lies in front of the bent-up tongue 2a. Now the tongue goes down and is moved a slight distance in the way towards the tube 9 (Fig. 19) so that the thread comes under the tongue. After this function, the thread guide 13 moves from the position shown in Fig. 19 somewhat away from the tube 9, i. e. from the position drawn in broken lines into that shown in full lines (Fig. 20). By this, the still existing open thread loop is tightened in the tongue 2a. Now the thread securing apparatus is approached in such a way that the tongue presser 15 comes over the tongue 2a. The presser 15 is moved downwards so that it presses the tongue 2a again flush with the peripheral surface of the tube 9, the thread end being thus clamped. The operation of the presser 15 for pressing the tongue down is brought about by the arm 46 of the shears 18 (Figs. 11 and 12), whereby said arm swivels anticlockwise round the axle 45 so that simultaneously with the pressing-down of the tongue presser 15 the shear blades 46 and 44 close and the thread is cut.

Incidentally, the thread gripper 17 (Fig. 13) has to make in the open position a movement on to the tube 9, whereby the thread—at the moment held tight between tongue 2a and thread guide 13—comes into the thread gripper 17; this has closed and simultaneously clamped the thread, i. e. shortly before the shears cut the thread. The conditions are illustrated in Figs. 21 and 22.

Subsequently the thread securing apparatus moves away from the tube 9 or spindle 1d and remains closed for a short while. The winding spindle 1d which, by its clamping part 7, holds the tube 9 under tension from within, is now loosened and drawn back, thus setting the wound bobbin tube free for further use.

Then, for the winding of a fresh empty tube, a magazine therefor (not shown) located above the winding spindle 1d will for instance be lowered so far that the lowermost tube in the magazine is brought coaxial to the axis of the winding spindle. The relaxed spindle 7, 1d projects into the new tube 9 to nearly the middle and clamps it. This position of the tube 9 on spindle 7, 1d is shown in Figs. 4 and 5.

Subsequent to this, the thread securing apparatus is approached to the tube until the knife 19 is introduced towards the middle of the tube 9 (Figs. 4 and 5) whereupon the tongue 2 is cut in the tube and bent away from it.

The thread gripper 17 which still keeps hold of the thread previously cut off and now forming the start, moves axially away from the tube until coming in front of the free tube end (Fig. 23) and then to the other tube side (Fig. 24) and thereafter again on to the tube (Fig. 25), whereby the thread will be pushed under the tongue 2. Now the tongue presser comes into action, in that the thread nipper or its gripping parts 50, 53 open and, by the set screw 65, 65a, the tongue presser 16 is depressed by its lever 61 onto the tongue 2, thus clamping the thread in the tongue 2. In the meantime the thread gripper has let free the end piece of the thread.

Through the lever arm 61 being set free, the tongue presser 16 is swung away under action of spring 66,

whereupon the thread securing apparatus is again led away from the tube 9.

Now, an abutment (not shown) is brought from above in front of the free end of the tube 9, and the winding spindle 7, 1d is slightly detensioned; this alines the tube 9 accurately against the stop by pushing same forwards and backwards, and clamps the tube firmly again by expanding from within. The thread guide 13 now lays itself sideways onto the tube (Fig. 26), and the winding machine is restarted automatically to wind the bobbin tube 9.

The particulars of my mechanism which are known per se in the art, shall now be described more in detail.

As shown in Fig. 30, a magazine 200 for empty bobbin tubes 9 is arranged above the front part of the winding spindle 7. The magazine 200 has at the lower side thereof an exit opening allowing only one bobbin tube 9 to escape from the magazine at a time. In order to prevent the bobbin tubes 9 from escaping from the magazine 200 two resiliently yielding locking members 201 are provided on the lower side thereof which engage the lowermost bobbin tube 9. The locking members 201 may be designed as leaf springs yielding whenever the lowermost bobbin tube 9 is forcibly removed downwards. One end wall 202 of the magazine 200 is shorter than the lateral walls thereof so that one end of the lowermost bobbin tube 9 is free so as to allow the winding spindle 7 to engage this bobbin tube. The opposite end wall, however, of the magazine 200 is produced and has an extension 203 extending beyond and below the lowermost bobbin tube so as to form a stop for the free end of the bobbin tube to be placed on the winding spindle 7. The magazine 200 is displaceable in vertical direction upwards and downwards by means of a guiding device (not shown) including a rod (not shown) and a cam (not shown) having a perimeter shown in Fig. 31 by the lowermost curve K. It should be noted that according to the curve K the magazine 200 is twice moved downwards by different amounts while the corresponding cam performs one revolution.

The winding spindle described hereinabove in connection with Figs. 1, 2 and 3 has an axially displaceable part 3 at the forward end of which the expander head 7 is provided which may be retracted by moving the part 3 backwards into the head 1d of the spindle when the bobbin tube 9 is to be exchanged on the winding spindle. The axial movement of the spindle part 3 is caused by means of the lever 4f being swingable about the axle 4g. As shown in Fig. 27 a second lever 210 is supported by the axle 4g, a pivot 211 connecting the second lever 210 with a rod 212 connected by a further pivot 213 with a lever 214 swingably supported on the frame of the machine by a pivot 215. The lever 214 is provided with a touch roller 216 rotatably supported by the same which abuts under the influence of a spring 217 against the perimeter of a cam 218. The spring 217 is connected with one end thereof to the lever 214 and with the other end to the stationary gear box 1a. The cam 218 is supported by a shaft 219 rotatably arranged on the frame of the machine, the shaft 219 carrying also the already mentioned cam (not shown) for moving the magazine 200. The perimeter of the cam 218 is shaped as shown by the curve J of Fig. 31.

The winding spindle comprises a centrally arranged mandrel 5 for expanding the expander head 7 by means of the conical head 6 shown in Fig. 1. The mandrel 5 is maintained by the spring 10 in such a position that the expander head 7 is expanded in order to clamp in position a bobbin tube 9 placed over the same. By means of the lever 11 the mandrel may be displaced so as to assume the ineffective position thereof in which the expander head 7 is not expanded. The lever 11 is connected with a shaft 11a connected with a second lever 220 as shown in Fig. 27. The latter is connected by a pivot 221 with one end of a rod 222 the other end of

which is coupled by means of a pivot 223 with a lever 224 arranged for rotation about the axle 215. A touch roller 225 is supported for rotation by the lever 224 which under the tension of a spring 226 engages the perimeter of a cam 227 arranged on the shaft 219 mentioned hereinbefore, the cam 227 having a perimeter shaped in accordance with the curve H shown in Fig. 31.

The three cams with the perimeters H, J, and K operate as follows:

When a bobbin tube 9 has been completely covered by thread, the mandrel 5 is advanced by means of the cams 227 and then the clamping action of the expander head 7 within the tube 9 is relieved. Then by means of the two cams 218 and 227 the spindle part 3 and the mandrel 5 are simultaneously retracted, the conical head 6 remaining always at a distance from the clamping part 8 of the expander head so that the latter is withdrawn from the fully wound bobbin tube and drawn into the spindle head 1d whereupon the finished bobbin drops downward. Already during these movements the magazine 200 starts to lower its position so as to be, after the dropping of the finished bobbin, in a position in which the tube 9 being lowermost in the magazine is situated coaxially in line with the winding spindle. This condition is shown in Fig. 27. Then the cams 218 and 227 control the motion of the spindle part 3 and the mandrel 5 (with the expander head being released) toward the front into the lowermost tube 9 of the magazine 200, however only so far that the tube is only pushed with part of its length over the expander head. Then the cam 227 allows the mandrel to retract a little so that the head 6 advances toward the part 8 and the expander head 7 is expanded so as to clamp the tube 9. Then the magazine 200 moves upward and causes the tube 9 to be removed from the magazine in opposition to the action of the locking members 201.

Now by means of the thread storing apparatus at the shell, the first tongue is punched out and the start of the thread clamped under the same. Subsequently the margin 200 moves again downwards, however only by so much that the extension 203 is placed in front of the free end of the tube 9 on the winding spindle. Then the cams 218 and 227 advance the mandrel 5 and the spindle part 3 farther so that the clamping action of the expander head 7 ceases to be operative and the latter is completely shifted into the tube 9 which is thereby locked in axial direction by the extension 203. Finally the cam 227 allows the mandrel 5 to withdraw a little so that the expander head 7 is expanded and clamps the tube 9. Now the magazine 200 moves again upward into its original position shown in dotted lines in Fig. 27. The shaft 219 has now performed a complete revolution and is uncoupled whereas the means for revolving the spindle are coupled with the same in order to wind a thread on the bobbin tube 9.

The stamping or cutting device of the thread storing apparatus shown in Figs. 4-7 of the drawings is driven by the shaft 23. According to Fig. 30 of the drawings a lever arm 230 is arranged on the axle 23 which is coupled by means of a joint 231 with one end of a rod 232, the other end of which is connected by a joint 233 with a lever 234 pivoted about an axle 235 supported by the frame of the machine. The lever 234 carries a roller 236 rotatably supported by the same which abuts against the perimeter of a cam 238 under the influence of a spring 237. The cam 238 is supported by the shaft 219 mentioned hereinabove and has a perimeter the form of which is shown by the curve D shown in Fig. 31. During each revolution of the shaft 219 the stamping or tongue-cutting device 12 is twice actuated for a relatively short period of time so as to cut during the first operation thereof the tongue for securing the end of the thread of a finished bobbin whereas during the second operation of the tongue-cutting device 12 the tongue is cut which secures the beginning of a thread to an empty bobbin tube

which has been placed in the meantime on the winding spindle.

The thread clip 14 shown in Figs. 8-10 of the drawings is provided with two control or driving axles 29 and 38. On the axle 29 is arranged, as shown in Fig. 30 of the drawings, a lever 240 connected with one end of a rod 242 by means of the joint 241. The other end of the rod 242 is coupled by a joint 243 with a lever 244 which, as shown in Fig. 30, is fulcrumed by the shaft 235 mentioned hereinbefore to the frame of the machine. On the lever 244 a contact roller 245 is supported which abuts against the perimeter of a cam 247 under the influence of a spring 246, the ends of which are connected, respectively, with the lever 244 and a hook 248 secured to the frame of the machine. The perimeter of said cam 247 is shaped according to the curve F shown in Fig. 31.

On the control axle 38 a lever arm 250 is arranged which is connected by a joint 251 with a rod 252 the other end of which is connected by a joint 253 with a lever 254 swingable about the shaft 235. A contact roller 255 is rotatably supported by the lever 254 and abuts under the influence of a spring 256 against the perimeter of a cam 257 shaped according to the curve E shown in Fig. 31. The spring 256 is connected with the ends thereof with the hook 248 and the lever 254.

The cam 247 causes the thread clip or pincers 14 to ascend during the greater part of the revolution of the cam into an elevated position shown in Fig. 30 which it assumes under the influence of the spring 246. Only when a projecting part of the cam 247 acts on the roller 245, the forward part of the clip or pincers 14 equipped with the working elements or nippers 26 and 27 is temporarily lowered, as shown in Fig. 30 in dotted lines. However, the other cam 257 allows during the greater part of the revolution thereof the lever 37 to assume a position being inoperative with respect to the nipper 26. Only when two recesses of the cam 257 travel under the roller 255, the lever 37 is rocked temporarily so as to move the nipper 26 away from the nipper 27 into the open position so as to grip or release the thread. During the first rocking movement of the cutting member or pincers 12 downward the pincers are opened and subsequently closed again when the pincers are in lowered condition so as to grip the thread. During the subsequent raising the pincers remain closed so as to lift the thread. During the next lowering of the pincers the same remain closed, and during the following raising of the same it is opened. The remaining operations of the thread clip or pincers 14 have been described hereinbefore in detail in connection with Figs. 16-19.

For actuating the tongue presser 15 shown in Fig. 11 and the shears 18 shown in Fig. 12, the axle 49 is provided on the thread storing device. As shown in Fig. 30 of the drawings, the axle 49 is equipped with a lever arm 260 coupled by means of a joint 261 with one end of a rod 262, the other end of which is connected by a joint 263 with a lever 264 swingably supported by the axle 235 mentioned hereinabove and connected with a roller 265 rotatably supported by the lever 264. Under the influence of a spring 266 the roller 265 is pressed against the perimeter of a cam 267 which is shaped according to the curve G shown in Fig. 31. As all cams so far described hereinabove, also the cam 267 is arranged on the shaft 219. The spring 266 is connected on the one hand with the lever 264 and on the other hand with a hook 268 secured to the frame of the machine.

The cam 267 effects during approximately half the period of one revolution thereof the closing of the shears 18 while during the remaining time the shears are in open position under the action of a spring 266. The tongue presser 15 for closing the tongues provided at the end of the tube 9 is actuated by the shears 18 themselves in opposition to the action of the spring 60 whenever the shears are closed.

The actuation of the second tongue presser 16 for clos-

ing the tongue serving for the actuation of the nipper 17 is effected also from the axle 49 and thus in dependence on the cam 267 described hereinabove, as shown in Fig. 30.

All the elements of the thread storing device are arranged on a table 270 which at each end thereof is guided by means of a guiding member 271 of trapezoidal cross-section in a dovetail groove of a bed 272 so as to be longitudinally displaceable, i. e. parallel to the axles 23, 29, 28 and 49 in order that the elements of the thread storing device may be brought into the correct positions with respect to the bobbin tube 9 when these elements have to operate. As shown in Fig. 28 the table 270 is provided with a rigid extension 273 which is connected by means of a joint 274 with one end of a rod 275 substantially parallel to the table 270 the other end of which is connected by means of a joint 276 with one arm of an angular lever 277 swingably supported by the frame of the machine about an axle 278. The other arm of the angular lever 277 is connected over a joint 279 with one end of a rod 280 the other end of which is positively connected over another joint 281 with a lever 282 being swingable about an axle 283 supported by the frame of the machine and supporting for rotation a roller 284, the lever 282 being under the influence of a spring 285 so that it abuts against the perimeter of a cam 286. The spring 285 is attached with one end thereof to the lever 282, the other end of the spring 285 being suspended from a hook 287 secured to the frame of the machine. The cam 286, as all the other cams, is attached to the shaft 219 mentioned hereinbefore and the perimeter of the cam 286 is shaped according to the curve B shown in Fig. 31 so that the table 270 during each revolution of the shaft 219 is several times moved to and fro in one and the opposite direction as the working phases require.

Each of the two beds 272 guiding the table 270, one of which only is shown in Figs. 28 and 29, is provided with a trapezoidal guiding rib 290 the longitudinal direction of which is at right angles to the longitudinal direction of the rib 271. The guiding rib 290 is guided for displacement in a corresponding dovetail groove 291 (Fig. 29) of the frame of the machine so that the table 270 by means of the beds 272 thereof may be moved, if desired, in a direction parallel to the winding spindle. To the lower side of each bed 272 a toothed rail 292 is secured which is engaged by a toothed sector 293 attached to a shaft 294 rigidly secured to a lever arm 295 connected over a joint 296 with one end of a rod 297 the other end of which is connected over a joint 298 with a lever 299 pivotable about an axle 300 supported by the frame of the machine. By the lever 299 is rotatably supported a roller 301 engaging under the influence of a spring 302 the perimeter of a cam 303 secured to the shaft 219 mentioned hereinabove. The spring 302 is connected with one end thereof to the lever 299 and with the other end to a hook 304 secured to the frame of the machine. The perimeter of the cam 303 is shaped according to the curve C shown Fig. 31 so that during any revolution of the shaft 219 several movements are imparted to the table 270 forward and backward in a direction parallel to the spindle in order that the operative elements of the thread storing device are brought into the required positions with respect to the bobbin tube 9 which has to be wound, or has been wound, with thread.

The shaft 219 carries a further cam (not shown) having a perimeter shaped according to curve A shown in Fig. 31. This cam serves for imparting to the thread guide 13 a motion transversal to the tube 9 as shown in Figs. 16-26. During a winding of the bobbin tube 9 the thread guide 13 is adjacent to the curved surface of the tube or the already generated winding. However, during the operation of the thread storing device the thread guide 13 is imparted a certain distance from the tube, this distance being variable as shown in Fig. 22. This is achieved by the last mentioned cam.

It should be noted that in practice several winding spindles may be arranged parallel to, and alongside one another, in which case for each winding spindle a separate thread storing device has to be provided, these devices, however, being arranged on one and the same table 270, the shafts 23, 29, 28 and 49 running through all these devices. Thus all thread storing devices are actuated positively and synchronously and driven by the same cams.

By the aforescribed means, independently controlled by preset program, the automatic production of wound bobbins, particularly of cardboard tubes, is provided.

What I claim is:

1. Method of making a wound bobbin, particularly a wound cardboard tube, comprising the steps of placing an empty bobbin tube in front of a winding spindle, introducing a controllable clamping part of the spindle into the bobbin to clamp same, securing the starting thread, winding the tube, securing the thus effected final thread, cutting the thread, releasing the clamping part, and retracting the same into the spindle, in that it is withdrawn from the wound tube which thus becomes free.

2. Method as claimed in claim 1, comprising the additional steps of introducing the clamping part of the winding spindle at first only so far into the bobbin tube to clamp this, that the free end of the tube projects beyond the clamping part to carry out the securing of the starting thread end, whereas for the winding operation the clamping part is relaxed and, upon accurate symmetrical adjustment of the bobbin tube in relation to the winding member, again tensioned, and the tube thereby clamped in its winding position.

3. Arrangement for making a wound bobbin, comprising, in combination, a winding spindle, a stationarily supported and rotatably driven bush, and a clamping part introduced thereto to clamp the bobbin tube, said clamping part capable of being axially displaced between a retracted position in the bush and a position projecting from it, and controllable in such a way that the bobbin tube is firmly clamped.

4. Arrangement as claimed in claim 3, said clamping part of said winding spindle including two members axially displaceable with respect to the bush, one of said members having an expandable part and the other an expander part adapted to influence the first part.

5. Arrangement as claimed in claim 4, said expandable part forming one extremity of a sleeve displaceably arranged in said guide bush and rotatably connected thereto, the other extremity being connected to a control member for operating the axial displacement.

6. Arrangement as claimed in claim 4, the expander part including a part displaceable in the spindle bush, one end of said part having an expander head cooperating with the expandable part, the other end thereof being connected to a control member for operating the endwise displacement.

7. Arrangement as claimed in claim 6, said part carrying at its rear end a cap with a tubular extension terminating in a shoulder which engages over the rear end of the spindle bush, a spring being inserted between said cap and rear face of the spindle bush, said shoulder cooperating with the control lever for displacing said part with respect to the spindle bush.

8. Arrangement as claimed in claim 3, a thread securing apparatus having a cutting member for producing cuts on the bobbin tube to secure the thread, a thread clip associated with the thread guide of the winding machine, a thread gripper and shears, said members being so controlled that the cutting member produces a cut in the middle section of the empty bobbin tube clamped on the winding machine, the thread clip being then caused to lead the starting thread into the cut to secure it, whereupon, with bobbin wound, the cutting member makes a cut at the free end thereof, the thread clip then introduces the final thread end into the cut to secure it,

and now the thread gripper clamps the thread between the cut in the tube and the thread guide of the winding machine, and the shears sever the thread.

9. Arrangement as claimed in claim 8, the thread securing apparatus including a cutting member for itself producing rising tongues from the periphery of the bobbin tube, a thread clip associated with the thread guide of the winding machine, a thread nipper, at least one tongue presser, and shears, said parts being so controlled that the cutting member cuts a tongue in the middle section of the empty bobbin clamped on the winding spindle, and bends the tongue away from the tube periphery, the thread nipper then laying the starting thread on the tongue while the thread is held clamped, whereupon, with wound bobbin, the cutting member cuts a tongue at the free extremity of the tube, and bends the tongue away, the thread clip then laying the final thread end on to the tongue, and the tongue presser again presses the tongue down flush with the periphery of the tube to thus secure the end thread, whereupon the thread is clamped by the gripper between bobbin tube and thread guide and severed by the shears.

10. Arrangement as claimed in claim 8, the members of the thread securing apparatus carrying out the different functions being mounted on the frame of the apparatus, a plurality of control members for said member of the thread securing apparatus, and further control members moving said apparatus as a whole.

11. Arrangement as claimed in claim 8, the cutting members including a knife introducible into the bobbin tube and a counter-knife led along outside on the tube, whereby the knife makes the cut on the tube from inside to outside and bends the cut tongue outwards, away from the material of the tube.

12. Arrangement as claimed in claim 11, the knife being formed as a lever, and a block swivably supporting said lever, said blade being mounted fast on the apparatus frame and forming the counter-knife.

13. Arrangement as claimed in claim 8, the thread clip comprising two nippers, one of which is formed as a lever mounted for swivelling about a control axle on the apparatus stand, while the other can swing on the former by a control axle on said stand and independent of the control axle of the former nipper.

14. Arrangement as claimed in claim 13, the second nipper mounted for swivelling on the first one being biased by a spring which tends to keep the nippers closed.

15. Arrangement as claimed in claim 14, the spring being at one end attached to the nipper formed as a lever and at the other end to a rod which can be pushed on said lever, one end of said rod engaging the swing nipper, while the other end cooperates with an arm of the respective control axle.

16. Arrangement as claimed in claim 15, said nippers being shaped so that, in their closed position, the thread is loosely held and guided.

17. Arrangement as claimed in claim 8, the thread securing apparatus including two tongue pressers for pressing down the cut-in and bent up tongues, one for the starting and the other for the final thread end.

18. Arrangement as claimed in claim 17, the tongue presser for pressing down the tongue to secure the final thread being operatively connected to the thread gripper.

19. Arrangement as claimed in claim 17, said tongue presser being operatively connected to the shears.

20. Arrangement as claimed in claim 8, and a common control axle actuating said thread gripper and said shears.

21. Arrangement as claimed in claim 8, one part of the shears being fixed to the stand of the apparatus, the other part being swingable by its control axle on the first part into the closed and open positions.

22. Arrangement as claimed in claim 21, and a spring biasing the movable blade of the shears, said spring tending to keep the shears open.

23. Arrangement as claimed in claim 19, the tongue

presser for pressing down the tongue to secure the final thread being arranged beside the shears and projecting with a driver into the path of the movable shear blade in such a way that the closed motion of the shear blade causes the tongue presser to be moved into operative position.

24. Arrangement as claimed in claim 8, one part of the thread gripper being fixed on a stand of the apparatus, while the other part can be swung by its control axle on the first part into the open and closed positions.

25. Arrangement as claimed in claim 24, and a rubber sleeve forming part of the clamping part mounted for swivelling on the stationary part of the thread gripper.

26. Arrangement as claimed in claim 24, the movable clamping part of the thread gripper being spring-biassed

10

15

so as to tend to keep the thread gripper in the closed position.

27. Arrangement as claimed in claim 8, the tongue presser for pressing down the tongue to secure the starting thread end being arranged beside the thread gripper, and a driver projecting from its movable part into the path of the tongue presser so as to cause the latter to move into operative position by the opening movement of the thread gripper.
